UNITED STATES PATENT OFFICE.

CYRENUS W. LENT, OF OAKLAND, CALIFORNIA, ASSIGNOR OF THREE-FOURTHS TO THEODORE SWIFT AND LOUIS SCHAFER, OF SAME PLACE, AND J. W. SWIFT, OF SAN FRANCISCO, CALIFORNIA.

ODORLESS CREMATORY.

SPECIFICATION forming part of Letters Patent No. 573,605, dated December 22, 1896.

Application filed December 9, 1895. Serial No. 571,541. (No model.)

To all whom it may concern:

Be it known that I, CYRENUS W. LENT, a citizen of the United States, residing at Oakland, county of Alameda, State of California, have invented an Improvement in Odorless Crematories; and I hereby declare the following to be a full, clear, and exact description of the same.

My invention relates to an apparatus for destroying garbage and other material by heat, and at the same time disposing of all noxious fumes arising from the operation, so as to produce what I call an "odorless crematory."

It consists in certain details of construction, which will be more fully explained by reference to the accompanying drawings, in which—

Figure 1 is a general view of my crematory. Fig. 2 is a vertical section through condenser and disinfecter. Fig. 3 is a longitudinal vertical section of the furnace and drying compartments. Fig. 4 is a lateral section on line *y y* of Fig. 3. Fig. 5 is a horizontal section showing the furnace-chamber E and the jet-tubes for the introduction of petroleum or other liquid hydrocarbon or gas. Fig. 6 is an enlarged sectional view of the combustion-chamber S and its attachments. Fig. 7 illustrates a sectional view of the pipes *a a' a''* for producing a suction for drawing the vapors out of the chamber U. Fig. 8 is a detail showing a portion of the spray-pipe *f*.

The furnace A may be of any suitable size and material. In the present case I have illustrated it as a structure about thirty feet in length by ten feet in height and eight feet wide, having near one end the fireplace B with a door-opening C, through which fuel may be introduced, and a bridge-wall D, over which the heated products pass. Behind this again is a suitably-grated floor E, which is designed to receive the material to be destroyed after the latter has been first dried and then delivered upon this grating.

It will be manifest that if it is desired to employ petroleum or other liquid hydrocarbon or gas to produce the heat, gas or hydrocarbon burner jet-tubes may be introduced through the walls of the apparatus, as shown

at F, preferably those from opposite sides discharging into the furnace intermediate to each other.

Above the grating E is a supplemental in- 55 closed chamber G, with a floor which is heated by the products of combustion in the furnace proper below. The chamber above this floor is a space of sufficient dimensions to receive garbage and material to be cremated or destroyed, which is introduced through open- 60 ings H in the top of the furnace.

The furnace, which is built of any suitable fire-resisting material, is so situated that the carts or wagons bringing the garbage can be driven directly over the top, and the con- 65 tents discharged through the openings H into the chamber G by simply removing the doors or covers I, which normally close these openings.

Directly in line beneath the openings H 70 are other openings or passages J, having movable doors K, arranged in any suitable manner to temporarily close the openings J and prevent the material from passing directly through into the furnace-chamber. These 75 supply-openings H are situated at suitable and convenient distances apart throughout the length of the furnace, and within the chamber G are vertical gratings L, intermediate between the openings, which serve to 80 prevent the soft garbage from flowing out in either direction too far away from the openings J, through which it is to be eventually delivered into the furnace. At the same time the gratings are sufficiently open to allow 85 any vapors to pass through them, and this is assisted by a draft-opening M near the front of the furnace opening into this chamber with a suitable controlling-damper, as will be hereinafter described. The material being dis- 90 charged into the upper chamber G is there dried, and any liquid contained therein will flow by gravitation to one side of the floor G', this floor being slightly inclined for that purpose. Upon the lower side of the floor is 95 a channel or gutter N, into which the liquid flows, and the gutter is slightly inclined from the front to the rear end of the furnace, so that the liquid will flow through this gutter toward the discharge end. The heat will vap- 100

orize a great portion of this liquid, and any liquid which may reach the rear end will pass out through a discharge-pipe O and be delivered into the vapor-escape pipe P, which leads 5 outwardly from the furnace-chamber, where the vaporization will be complete. The heat in the chamber G will usually be sufficient to vaporize the greater portion of the liquid, and this vapor and that arising from the drying 10 out of the garbage will pass out through a pipe O', leading from the upper part of the upper chamber into the discharge pipe or passage P.

When the garbage is sufficiently dried to 15 be properly burned, the doors K are opened, and the dried material, falling through them upon the grating or hearth E, will there be burned, and vapors arising from this combustion pass out through the passage P, uniting 20 with the vapors which are being discharged from the upper chamber.

Door-openings Q are made through the sides of the furnace above the grating E, and by means of suitable slices or tools the cinders arising from the destruction of the material are broken up, so as to pass through the grating-floor and into the ash-pit beneath, from which it can be withdrawn from time to 30 time through doors or openings R, opening into the sides of the ash-pit.

The passage P is of considerable length, as much as one hundred feet, more or less, as found desirable, and at some point within this passage not far from the furnace is made 35 an enlargement or combustion-chamber S. This chamber may be of any suitable form and is designed to allow the expansion and more complete combustion of unconsumed gases which have reached that point through 40 confined passages or flues where such combustion cannot effectually occur even if there is plenty of air for the purpose. Beyond this combustion-chamber is an exhaust-fan T or equivalent draft-producing device, connecting 45 with the passage P in such a manner as to produce a strong draft through it, and this draws the products of combustion into the passage and also draws air through the damper M in the front of the upper chamber, and 50 this air being heated helps to dry the material in the upper chamber and passes with the vapors out through the passage O' and into the discharge-passage P.

U is a receiver, which is made of any suitable form and size. In the upper part of this receiver pipes V are arranged to return upon each other backward and forward from one end to the other. These pipes are perforated at the bottom, and they receive a supply of 55 water through a pipe and cock V'. This water passing through the pipes V discharges into the chamber U and condenses the vapors which have arrived in the chamber from the apparatus, as previously described. Any vapors that are sufficiently condensed in this 60 chamber will pass out through passages W in the lower part and into the condensing-cham-

ber Y, which is provided in the upper part with a series of water-jet pipes Z, corresponding to those shown at V in the receiver above. 70

In order to withdraw any remaining uncondensed vapors from the receiver, I have shown pipes a opening outwardly from the sides of the chamber and leading downwardly into the chamber Y, where they terminate 75 near its bottom.

b is a discharge-passage opening from the side of the condensing-chamber Y at such a height that the chamber will remain constantly partially filled with water. Surrounding the pipes a are the mushroom or bell shaped caps c, open at the bottom and having their lower edges just dipping into the surface of the water in the condensing-chamber Y. The pipes a connect by means 85 of T's a' with a supply-pipe a'', through which water is delivered into the vertical downwardly-extending portion of the pipes a, and this produces a draft or suction action, which constantly draws the vapors out of the 90 receiving-chamber U and delivers them into the condensing-chamber Y. These vapors pass down the vertical pipes a to the bottom and beneath the water in the chamber Y and are condensed thereby. Any incondensable 95 smoke or vapors will arise through the water beneath the bell-shaped attachments c, where they gradually escape around the edges in a purified form with whatever air may have passed into the apparatus by the action of 100 the fan and draft previously described. This air may be discharged in any suitable manner and will be practically freed from all noxious vapors and smells. I have shown the pipe b so arranged as to discharge both 105 air and liquid into a final disinfecting-chamber d, having spray-pipes f, an air-discharge pipe e, and an overflow g; but the number of chambers following the condenser will depend upon the perfection of the condensation 110 and the necessity for depriving the escaping products of noxious qualities.

The pipe e is here shown extended back to the furnace, into which it discharges any uncondensed or noxious vapors, to be again 115 passed through the furnace, where they will be destroyed or rendered innocuous. This also adds to the draft through the furnace proper.

Having thus described my invention, what 120 I claim as new, and desire to secure by Letters Patent, is—

1. A crematory consisting of an inclosed furnace adapted to burn the material, a superposed closed drying-chamber having feed- 125 openings at the top with controlling-doors, coincident openings beneath the feed-openings leading from the drying to the furnace chamber with doors whereby communication between the two is controlled, a transversely inclined floor extending from one side to the other of the drying-chamber and a longitudinal channel or channels at the lower side of the floor to receive unvaporized liquid con- 130

tained in the material delivered into the dry-
ing-chamber, a pipe with which the channel
connects and a main discharge-passage from
the furnace and drying chamber into which
5 the pipe also leads.

2. A crematory-furnace consisting of an
inclosed furnace-chamber having a grated
floor, means for applying heat therein for the
destruction of its contents, door-controlled
10 openings at the sides for the introduction of
implements to break up and discharge the
burnt mass through the grated floor, a re-
ceiving-pit beneath with similar openings for
the removal of the clinker after it falls through
15 the grate, a closed drying-chamber situated
above the furnace-chamber having door-con-
trolled openings for the introduction of the
material to be treated, vertical grated dia-
phragms fixed at intervals in the length of
20 the drying-chamber to limit the spread of the
material, a draft-opening for the introduc-
tion of air at one end of said chamber, and a
discharge-passage at the opposite end for the
delivery of vapors, and door-controlled open-
25 ings in the floor of the chamber through
which the material is delivered by gravita-
tion into the furnace after being dried.

3. A cremating apparatus consisting of an
inclosed furnace, with means for applying
30 heat for the destructive distillation of its con-
tents, a grated floor and door-openings for
the agitation and discharge of the burnt ma-
terial, a superposed inclosed drying-chamber
with receiving and discharge openings, and
35 an air-inlet passage and valve at one end, a
discharge-pipe leading from the furnace to
a condenser, an inclined floor with channel
for the collection of the liquid portions of the
material delivered into the drying-chamber,

said channel connecting with the discharge- 40
passage from the furnace, a second discharge-
passage from the upper part of the drying-
chamber for the conduction of vapors there-
from to the main discharge-pipe, an enlarged
45 combustion - chamber situated within the
length of said pipe, and a draft apparatus
whereby the vapors are drawn from both fur-
nace and drying chamber and delivered into
the condenser.

4. A cremating apparatus consisting of a 50
furnace-chamber, a superposed drying-cham-
ber with doors whereby access may be ob-
tained to the two for the introduction and
removal of the material, channels in the floor
55 of the drying-chamber for the collection of
liquid portions of the mass, a main dis-
charge-passage leading from the rear of the
furnace to the condenser, passages connect-
ing respectively with the liquid-collecting
60 channels and the upper part of the drying-
chamber and delivering into the main fur-
nace discharge-pipe, a combustion-chamber
interposed between the furnace and the con-
denser, a draft apparatus whereby the prod-
65 ucts of combustion and the vapors from the
drying-chamber are drawn into a discharge-
pipe and delivered thence into a condenser,
a condenser within which the vapors are con-
densed and a disinfecting-chamber into which
70 the uncondensed vapors and products of con-
densation are delivered from the condenser.

In witness whereof I have hereunto set my
hand.
